UNITED STATES PATENT OFFICE.

FRANKLIN S. MCKENNEY, OF DETROIT, MICHIGAN.

DESIGN FOR A FASTENER.

SPECIFICATION forming part of Design No. 22,978, dated December 19, 1893.

Application filed November 20, 1893. Serial No. 491,492. Term of patent 14 years.

To all whom it may concern:

Be it known that I, FRANKLIN S. MCKENNEY, a citizen of the United States, residing at Detroit, in the county of Wayne, and State of Michigan, have invented and produced a new and original Design for Fastening or Attaching Devices, of which the following is a specification, reference being had to the accompanying drawings, illustrative thereof, in

which—

Figure 1 is a view in perspective, and Fig. 2 is an inverted plan, these views being necessary to fully illustrate my design.

The leading features of my design for a fastening or attaching device, consists of the head, a portion of which is substantially crescent shaped, and having the ends of the crescent bent inward toward each other, and into the crescent, the entire head thus substantially resembling the under side of a horse's hoof. The extremities of the metal from which the fastening or attaching device is made, after being thus bent inward toward

each other and into the crescent, are then bent at an angle to the plane of the head to form 25 attaching prongs, the head adjacent to said prongs projecting laterally outside thereof on every side to form a marginal seating flange around the prongs as shown. The inwardly projecting portions after being bent inward, 30 are also diverged before being bent at an angle to form the attaching prongs.

In the drawings, A represents the head, a , and a' the inwardly projecting portions, and a^2 and a^3 the attaching prongs. 35

A' is the marginal flange.

What I claim as my invention is—
The design for a fastening or attaching device, substantially as shown and described.

In testimony whereof I sign this specification in the presence of two witnesses.

FRANKLIN S. MCKENNEY.

Witnesses:

N. S. WRIGHT,
H. P. WHEELER.
